UNITED STATES PATENT OFFICE.

OTTO ROTTEN, OF BROOKLYN, NEW YORK.

COWL.

SPECIFICATION forming part of Letters Patent No. 352,573, dated November 16, 1886.

Application filed June 1, 1886. Serial No. 203,805. (No model.)

To all whom it may concern:

Be it known that I, OTTO ROTTEN, a citizen of the United States, residing at Brooklyn, in the county of Kings and State of New York, 5 have invented certain new and useful Improvements in Cowls; and I do hereby declare that the following is a full, clear, and exact description of the same, reference being had to the annexed drawing, making a part of this specification, and to the letters and figures of reference marked thereon.

The present invention has relation to certain new and useful improvements in cowls for the tops of chimneys or ventilating shafts, 15 and the object thereof is to improve their construction, whereby the ascending column of smoke, gas, or foul air is unobstructed in its course and free to escape, thus providing a cowl effective in its purpose and certain in its 20 action. These objects I attain by the construction substantially as shown in the drawing, and hereinafter described and claimed.

In the accompanying drawing I have shown a perspective view of my invention, the hollow column or shaft being partly broken away to show the lower end of the supporting-rod 25 and transverse braces. This column or shaft A may be of any suitable diameter and length desired, and the braces *a* are secured to the 30 interior thereof, as shown, any number being used as found preferable, the rod or spindle *b* supported thereby in the usual manner.

The cowl B may be of any of the usual forms, and is provided at its lower end with a converging plate or deflector, C, having side 35 flanges, *c*, and a collar, *d*, which fits over the upper end of the hollow column or shaft A and rotates thereon, the deflector C carrying with it the cowl B. The deflector C has outwardly-curved vanes D upon and against which the current of air acts, causing a rotation of the cowl and deflector, the vanes bringing the latter to face the wind or current of air. Thus 40 by the inclination of the converging plate constituting the deflector the horizontal currents of air are deflected upward, as shown by the arrows, and ejected through the cowl, thereby causing a current of corresponding velocity 45 to ascend from the hollow column or shaft, from which it is drawn by the comparative 50 vacuum caused by the passage of air over, upward, and around the lateral space *e*, between the lower end of the cowl and the end of the column or shaft.

When no wind is blowing, there is no obstruction to ascending column of sewer-gas, which heretofore formed an obstruction in cowls of ordinary use, and the natural flow of air over the column or shaft has its full play without any obstruction, the peculiar form of 55 the deflector, as hereinbefore described, directing the wind up and around it, causing on its lee side an exhaust.

A very important feature of my invention is locating the lower end of the cowl B some 60 distance above the end of the column or shaft A, so as to form an air space or passage between them, allowing the air to act on the column or shaft with greater effect than were the cowl set down over the end of the same, the 65 current of air passing directly over the open end of the shaft or column through the space *e*. A natural flow of air is always secured over the upper end of the hollow shaft or column, the exhaust caused by the deflector to windward 70 collecting another flow of air to rush over and around the sides, no obstruction in the shaft or column to the ascent of air, soot, or gas being presented, and consequently cannot clog by soot, snow, or rain freezing thereon. 75

When there is little or no air stirring it offers no impediment to ascending current, and draws air with less wind than the cowls in ordinary use, and allows no downward current.

I am aware of the construction disclosed by 80 the expired patent of C. F. Thomas, No. 14,171, granted January 29, 1856, and I do not claim, broadly, any feature shown in said patented construction.

Having now fully described my invention, 85 what I claim as new, and desire to secure by Letters Patent, is—

The combination, with a hollow shaft or column, of a deflector consisting of an inclined plate provided with sides converging toward 90 the column, a collar attached to said deflector and mounted on the column, and a cowl, B, the lower end of which is supported by the deflector above the upper end of the column, 95 substantially as set forth.

In testimony that I claim the above I have hereunto subscribed my name in the presence of two witnesses.

OTTO ROTTEN.
